UNITED STATES PATENT OFFICE.

OSCAR ANDERSON, OF RÅSUNDA, SWEDEN.

CONTROL-SWITCH FOR ELECTRICALLY-OPERATED MEASURING APPARATUS.

1,292,221.

Specification of Letters Patent. Patented Jan. 21, 1919.

Application filed November 11, 1916. Serial No. 130,926.

To all whom it may concern:

Be it known that I, OSCAR ANDERSON, a citizen of the Kingdom of Sweden, residing at Råsunda, Sweden, have invented new and 5 useful Improvements in Control-Switches for Electrically-Operated Measuring Apparatus, of which the following is a specification.

This invention relates to a control switch 10 for electrically operated measuring apparatus, especially such apparatus adapted to measure certain quantities of liquids, powdered materials or the like. In apparatus of that kind it is frequently desirable, that 15 the apparatus be so adjusted, that, after a certain number of measurements, it is automatically made inoperative.

One object of this invention is the provision of a control switch, by means of 20 which a measuring apparatus of the type above specified may be made inoperative after any desired number of measurements.

A further object consists in the provision 25 of a control switch of the said kind provided with an electromagnetic escapement wheel mechanism designed to be put in the control circuit of the measuring apparatus and comprising an escapement wheel adapted, in a certain position, to break said circuit.

30 A preferred embodiment of the invention is illustrated in the accompanying drawing in which:—

Figure 1 is a front view of the switch with removed cover. Fig. 2 is a sectional view 35 on line A—A in Fig. 1. Fig. 3 is a front view of the switch with the cover in place, and Fig. 4 is a section on line B—B in Fig. 1.

In the construction shown, the control 40 switch comprises an escapement wheel mechanism consisting of an escapement wheel 1 and a double-armed pawl 2. The escapement wheel is pivotally mounted on a shaft 3 and actuated by a spring 4 tending 45 to hold the wheel in a certain position. The pawl 2 is pivoted to a shaft 5 and secured to the armature 6 of an electromagnet 7. A spring 20 tends to hold the pawl in the position in which the armature 6 is removed 50 from the electromagnet 7. The circuit of the electromagnet comprises two contact springs 8 and 9, the former 8 of which extends into the path of movement of a projection 10 secured to the wheel 1. The contact spring 8, which, owing to its elasticity, 55

tends to be in contact with the spring 9, is normally kept out of contact with the latter by means of a shoulder 11 formed on a spring 12 (Fig. 4).

All the members above mentioned are 60 enclosed in a casing 13 provided with a cover 14. The shaft 3, which extends through said cover, supports outside the same a pointer 15, which is to be operated by hand and is connected with the wheel 1, so that, 65 on turning the pointer, the wheel is turned at the same time. The pointer may be adjusted to any one of the positions indicated by the figures 0 to 10 (Fig. 3). A stop-pin 16, Fig. 2, may be inserted into holes formed 70 in the cover 14, so as to prevent the pointer from passing a certain position. Passed through the cover 14 is a pin 19 provided with a spring-actuated push-button 18 and serving to so actuate the spring catch 12, 75 that the contact spring 8 is released.

The switch described above is designed to 80 control the number of consecutive measurements effected by electrically controlled apparatus for measuring certain quantities of liquids, powdered materials and the like, as for instance a fluid measuring apparatus of the kind described in my patent application Serial Number 15110, filed March 17, 1915. In said measuring apparatus the circuit of 85 the apparatus is closed, as soon as certain contacts in the apparatus are closed. Then the apparatus is capable of performing a measuring operation, during which the circuit is again broken and remains broken, 90 until the apparatus is ready for the next measuring operation.

The electromagnet 7 and the contacts 8, 9 are connected in series with said circuit of the measuring apparatus. 95

If for instance, the measuring apparatus shall effect five measurements and then be made inoperative, the pointer is adjusted to the position marked by the figure 5, and the stop-pin 16 may at the same time be inserted into the corresponding hole 17, so as to prevent the pointer from passing the position 5. Then the button 18 is pushed, and on account thereof the contact-spring 8 is released and by its own elasticity brought in 100 contact with the contact spring 9, whereby the circuit of the measuring apparatus is closed and said apparatus started.

In accordance with the occurrences in the circuit of the measuring apparatus the cir- 105

110

cuit of the electromagnet 7 is closed and broken one time at the first measuring operation, and owing thereto the armature 6 is attracted and released one time, so that 5 the pawl 2 is caused to move to and fro one time, and during this movement of the pawl the spring 4 turns the wheel 1 from position 5 to position 4.

When the circuit of the measuring apparatus is again closed and broken at the next 10 measuring operation, the armature 6 is anew attracted and released, and the wheel 1 is caused to move to position 3 and so on.

When after the fifth measuring operation 15 the wheel 1 reaches the zero-position, the projection 10 actuates the contact-spring 8, so as to move the same out of contact with the contact-spring 9. Thereby the circuit of the measuring apparatus is definitely broken, 20 and, therefore, any closing of the contacts of the measuring apparatus will be of no influence. When the spring 8, on moving in the direction from the spring 9, reaches the position in front of the shoulder 11 of the

spring 12, the latter moves outward thus 25 locking the spring 8.

Having now described my invention, what I claim as new and desire to secure by Letters Patent is:

A control switch for electrically operated 30 liquid measuring apparatus, comprising a closed casing, a rotatably mounted wheel within said casing, an operating pointer for said wheel outside said casing, a retracting spring for said wheel, a spring - operated 35 pawl to control the retracting movement of said wheel, an electro-magnet to control said pawl, connections to connect the electromagnet to the circuit of the measuring apparatus to be controlled, contact springs in said 40 connections, manually operable means for initially closing said springs, and means on the rotatable wheel to open the springs in a certain position of the wheel.

In testimony whereof I have signed my 45 name.

OSCAR ANDERSON.
